UNITED STATES PATENT OFFICE

139,844

DESIGN FOR A COMBINED DRILL AND COUNTERBORE

Lawson A. Smith, Los Angeles, Calif., assignor to
Robert H. Clark, Los Angeles, Calif.

Application May 5, 1944, Serial No. 113,480

Term of patent 14 years

(Cl. D54—14)

To all whom it may concern:

Be it known that I, Lawson A. Smith, a citizen of the United States, residing in the city of Los Angeles, county of Los Angeles, and State of California, have invented a new, original, and ornamental Design for a Combined Drill and Counterbore, of which the following is a specification, reference being had to the accompanying drawing, forming a part thereof.

The figure is a perspective view of the tool showing my new design, showing one side of the tool, the other side being the same in appearance.

I claim:

The ornamental design for a combined drill and counterbore, as shown and described.

LAWSON A. SMITH.
